CLAIM

The ornamental design for a serrated ultrasonic knife tip, as substantially shown and described.

DESCRIPTION

FIG. 1 is a perspective view of a serrated ultrasonic knife tip showing my new design.

FIG. 2 is an enlarged partial view thereof, of the cutting tip portion.

FIG. 3 is a right side elevation view thereof, the left side being a mirror image thereto.

FIG. 4 is a rear end plan view thereof.

FIG. 5 is a front end plan view thereof.

FIG. 6 is a top plan view thereof.

FIG. 7 is a bottom plan view thereof; and,

FIG. 8 is a cross-sectional view thereof taken along the line 8—8 of FIG. 6.
